UNITED STATES PATENT OFFICE.

FRANK WILCOME, OF PAWTUCKET, RHODE ISLAND, ASSIGNEE TO HEMPHILL MANUFACTURING COMPANY, OF CENTRAL FALLS, RHODE ISLAND, A CORPORATION OF RHODE ISLAND.

CIRCULAR-KNITTING MACHINE.

1,129,262.

Specification of Letters Patent. Patented Feb. 23, 1915.

Application filed April 20, 1914. Serial No. 833,268.

To all whom it may concern:

Be it known that I, FRANK WILCOME, citizen of the United States, residing at Pawtucket, Rhode Island, have invented certain new and useful Improvements in Circular-Knitting Machines, of which the following is a specification.

My invention comprises an organization for operating the yarn feed fingers of a circular stocking knitting machine and it consists in the features and combination and arrangement of parts hereinafter described and particularly pointed out in the claims.

In the drawings Figure 1 is a front view 15 of a knitting head with my improvement attached. Fig. 2 is a plan view of the yarn finger lifting levers, and associated parts, the latch ring together with the yarn fingers carried thereby being omitted. Fig. 20 3 is a view looking from the right of Fig. 1 with the knitting head omitted. Figs. 4 and 5 show in plan and in side elevation a guide box for lifting pins. Fig. 6 is a detail view 25 of the lifting pin for the splicing yarn finger. Figs. 7 to 10 are details.

In the drawings 1 is the knitting head. This may be of various types, spring needle or latch needle, but for convenience I show the general form known as the Banner, being disclosed in Letters Patent of the United States granted to Hemphill No. 933,443, dated September 7, 1909.

2 is the latch ring which is movable in relation to the knitting head in the ordinary manner, being pivotally mounted off to one side so that it may be swung upwardly and backwardly to permit access to the needles for transferring or other purposes well understood by knitters. This latch ring carries pivotally mounted thereon at 3 a series of yarn fingers, one of these 4 being shown in Fig. 1 in its elevated or out of work position while another finger 5 is shown in dotted lines in its lowered position to deliver its yarn to the needles, this finger being for the splicing yarn for making the high splice and double sole. Each of the yarn fingers is under pressure of a lever 6, these levers being pivoted at 6 to an extension of the latch ring and acted on by a spring 7 suitably mounted in the latch ring, there being one of these levers 6 with its spring for each of the yarn fingers. Each yarn finger is swung upwardly to its inoperative or out of work position by a lever

8, one for each yarn finger and these levers are pivotally mounted at 9 to a standard 10 suitably mounted on the fixed base 11 of the knitting head. This standard, as in common practice, serves as a support for the latch ring, said ring having an adjustable screw stop 12 to bear on the top of the standard at 13. These levers are raised by pins 14, 14 guided vertically in a box or matrix 15 fixed to the standard 10. Fig. 2 shows in plan the standard 10 with the levers 8 and it will be seen that there are six of these and consequently in the present example of my invention there are six yarn fingers. The matrix or box 15 for guiding the lifting pins 14 may be of various forms and the pins also may be of various shapes, but in the particular construction shown the guide box is made up of separate pieces or sections 15', fitting against each other at their lower thickened portions as shown in Fig. 5 and separated from each other at their upper ends to form guide spaces or passages to receive and guide the lifting levers 8. These sections or leaves are also formed with guide ways 16 for the lifting pins and while these pins may be of various shapes, as above indicated, in the particular construction shown they are square in cross section and the guide ways 16 are formed to correspond. The separate sections of the matrix or guide box are held together by pins 17, Fig. 4 shown in dotted lines.

The lifting pins are arranged in echelon and the pin 14* which raises the splicing, 90 yarn guide 5 through the lever 8 at the rear is thicker than any of the other pins and at its lower end it has a notch 18 in its side face which receives the end of an arm 19, hereinafter referred to, for raising and 95 lowering the pin. The pin is also raised by a pattern controller lever 20 and there is a lever like this one for each of the other lifting pins, these other levers being marked 20*, Figs. 1, 2 and 3. These levers 20 and 100 20* extend substantially horizontally to the front of the machine and are pivotally mounted on a rod 21 held by a post 22 fixed to the base plate of the machine. These levers are operated by wires, one of which is 105 shown at 23 in Fig. 3. These wires extend down at the front of the machine outside the frame and at their lower ends these wires are connected to levers like the pattern levers 24 of the Hemphill patent above men- 110

tioned, which are operated by the pattern drum of the Hemphill machine. These connections operate the levers 20, 20^x and control the vertical positions of the pins 14, 5 14^x and thus determine whether the yarn fingers will be in or out of work. While the leg, heel and toe are being knit the lever 20 is operated by the described connections leading to the pattern drum to hold the pin 10 14^x up and thus the splicing yarn finger 5 will be held up out of work. When the high splice or double sole is to be knit, however, the lever 20^x is operated to allow the pin 14^x to be lowered and the spring 7 corresponding to the splicing yarn finger operating through the proper lever 6 the splicing yarn finger will be lowered into work. This splicing finger when lowered by the lowering of its pin 14^x is brought within 15 range of operating mechanism which will raise and lower the splicing yarn finger as in ordinary practice. This operating mechanism consists of the arm 19, above mentioned, which is connected adjustably to a 20 vertically movable slide 24 which is guided in the standard 10, being substantially inclosed within this standard as shown in dotted lines in Fig. 1. This slide is guided by the walls of the standard and by a gib 25 held between the walls of the standard by 25 screws 26.

The slide is recessed or of channel form as shown in dotted lines at 27, Fig. 2, and this portion receives the rear end of the arm 19 which is pivoted between the walls of this channelled part on a pin 28. The rear end of the arm 19 has projections 29 borne upon by adjusting screws 30 held by the slide and thus the arm 19 can be tipped up or down, 35 and thus through its engagement with the notch 18 of the lifting pin 14^x the splicing yarn finger can be adjusted accurately to its work. The slide 24 is operated vertically by a cam 31 connected to the clutch block *b*, 40 which block is similarly marked in the Hemphill patent above mentioned, the said cam bearing on a roller 32 journaled on a pin 33 connected with the lower end of the slide. This cam moves the slide upwardly 45 while its downward movement is due to gravity assisted by the spring 7 belonging to the splicing yarn finger and a spring 34 within the standard which at its lower end bears on a shoulder of the slide 24 and at its 50 upper end bears on a pin fixed in the standard. The clutch block *b* is operated by a lever *b'* in changing from round to reciprocating knitting or the reverse, the gear *i'* imparting movement for round knitting to 55 the rotary cylinder of the knitting head while the gear *i''* imparts the movement for reciprocating knitting, this gear being operated from a segmental gear *i'*, these parts being substantially the same as illustrated 60 in the Hemphill patent above mentioned.

In Fig. 1 the parts are in the position for splicing, the clutch block *b* being shifted to the right so that the drive takes place through the gear *i'* for round knitting, the cam 31 having now been shifted by the 70 movement of the clutch block rightward to a position under the roller 32 of the vertically movable slide and this slide together with the splicing yarn finger having been let down for work, the cam will give the 75 necessary vertical reciprocations to the slide to alternately throw the splicing yarn finger into and out of work. The slide 24 is limited in its vertical movement by a pin 33^x therein fitting in a recess of the gib 25. When the leg or the heel and toe is being knit the lever 20 lifts the pin 14^x and this in turn lifts the splicing yarn finger by means of the lever 8 corresponding thereto and the lifting of the pin 14^x also raises 85 the arm 19 together with the slide 24 and thus raises the roller 32 out of range of the cam 31, assuming that the machine is knitting the leg and that the cam 31 is in its right hand position as shown. It will be 90 understood that when the heel and toe is being knit the clutch block *b* would be shifted leftward and the cam 31 would thus be out of the vertical plane of the roller 32, but notwithstanding this the lever 20 would 95 maintain the slide 10 and the splicing yarn finger in its elevated position to hold this yarn finger 5 out of work and thus the roller 32 would remain in its elevated position and the rightward movement of the 100 cam 31 would not be interfered with.

As shown in Figs. 1 and 4 the front section of the matrix or box 15 is extended downward and is provided with vertical slots in which the rear ends of the levers 20, 20^x are guided and sustained against lateral displacement. It will be observed that the slide 24 provides a simple and direct form of connection between the operating cam and the lifter of the splicing yarn finger 5. This slide while inclosed in the post is readily accessible from the open side of the post or standard 10 indicated at *x*, and as this slide carries the arm 19 this can be readily adjusted to alter the throw of the yarn splicing finger 5 by adjusting the screws above mentioned. By the use of the vertically moving lifting pins operating in connection with the lifting arms or levers 8, the necessary amount of movement may be secured in lifting and lowering the yarn feed fingers and at the same time little room is needed and thus the mechanism is adapted to go onto a machine having a low needle cylinder, for lifting pins having a short stroke may be employed because the movement of these pins is multiplied by the levers 8. The standard or post 10 carries the slide 24, the guide box or matrix 15 with the lifter pins, and the lifting arms or levers 8 115 120 125 130

and all these parts can be removed from the machine and replaced as one unit by removing and replacing the post or standard. The standard has a foot portion shown in Fig. 5, held by screws 35 to the plate 11 of the machine frame. It is desirable sometimes to raise the thread fingers higher or lower with reference to the top of the needles and it has been customary on the type of machine 10 known as the Banner, to bend the levers operated by the pattern drum to get this result. I have provided adjustable connections between the pattern drum levers and the thread levers whereby the operator or adjuster may lengthen or shorten the links to give the thread carriers more or less movement. I have shown two forms of adjustment, either one of which accomplishes the result aimed at.

20 The form shown in Fig. 8 is composed of a link 23, both ends having hooks 23^a to engage pins in the levers 20 and in the pattern drum levers 20^a which are operated by the pattern drum, a portion of which is shown at 23^b. The link in this case is made in two parts, one part being threaded into the other part at 23^x and when it is desired to vary the length of this link it is only necessary to unhook one end of the link and give it a turn and when it is hooked into the levers no check nuts are required to hold it in its proper adjustment, the hooked end of the links fitting in the forked ends of the levers as at 20'.

35 In the form shown in Figs. 9 and 10 the link is made with a two part coupling 36 and the two link ends are rigidly fixed to the two part coupling. One part of the coupling 37 is attached to one link end and the other part 38 to the other link end by striking in the metal at 39. One link end 40 projects through its coupling into the other coupling member and can move freely in the other half of the coupling. The two halves 45 of the coupling are adjustably connected by a screw 41 passing freely through one and threaded with the other, and a jam screw 42 is used in the same threaded hole with the adjusting screw. To get any desired length 50 of link it is only necessary to turn the adjusting screw 41 as desired, and it may be locked by the jam screw 42. When so connected the machine may be taken apart without changing the adjustment and there 55 is no liability of displacement as in the form first described. When it is desired to remove the links without taking the machine apart it is only necessary to remove entirely the adjusting screw and thereby separating 60 the two halves of the coupling and links and when the two halves are put together again they do not require readjustment as the jam screw determines the positioning of the two halves of the coupling. The object aimed 65 at is an adjustable link connection between

the operating ends of the two sets of levers, or to provide an adjustment between the yarn finger and its operating connection.

I claim:

1. In combination in a circular knitting machine, a plurality of yarn feed fingers, including a splicing yarn finger, a cam and cam shaft, a vertically movable slide operated by the cam directly, means for guiding the slide and a connection between the slide 70 and the splicing yarn finger, said connection comprising a lifting pin operated by the slide and a lifting lever operated by the pin and means for guiding the lifting pin, substantially as described.

2. In combination in a circular knitting machine, a plurality of yarn feed fingers, including a splicing yarn finger, a cam and cam shaft, a vertically movable slide operated by the said cam directly, means for 80 guiding the slide, an arm carried by the slide extending substantially horizontally, and lifting means operated by said arm to lift and lower the splicing yarn guide, said arm being adjustable vertically in relation 85 to the yarn finger and slide, substantially as described.

3. In combination in a circular knitting machine, a plurality of yarn feed fingers, including a splicing yarn finger, a cam and 90 cam shaft, a vertically movable slide operated by the said cam directly, means for guiding the slide, an arm carried by the slide extending substantially horizontally, and lifting means operated by said arm to 95 lift and lower the splicing yarn guide, said arm being pivotally mounted on the slide and adjusting means for holding the arm in different angular positions about its pivot, substantially as described.

4. In combination in a circular knitting machine, a plurality of yarn feed fingers, including a splicing yarn finger, a vertically moving slide, a cam shaft and cam operating said slide directly, means for guiding 100 the slide, a lifting pin vertically movable, an arm connecting the slide with said pin, and a lever for lifting the pin together with the arm and slide, said pin lifting and lowering the splicing yarn finger and the slide 110 when it is raised and lowered by the lever, substantially as described.

5. In combination in a circular knitting machine, a plurality of yarn fingers, a series of lifting pins movable vertically, means 120 for guiding said lifting pins, levers interposed between the lifting pins and the yarn feed fingers, a post supporting the pivoted levers and the guide means for the lifting pins, and levers for operating the lifting pins, said levers extending and operating in planes substantially at right angles to the vertical planes in which the yarn feed fingers move, substantially as described.

6. In combination in a circular knitting ma- 130

chine, a plurality of yarn feed fingers, a plurality of lifting pins for said fingers, levers between said pins and yarn feed fingers, a box for guiding said lifting pins and levers consisting of a series of sections with guides formed therein for the lifting pins and separated at their upper ends to form 5 guide spaces for the levers and levers for

operating the lifting pins, substantially as described. 10

In testimony whereof, I affix my signature in presence of two witnesses.

FRANK WILCOMB.
